UNITED STATES PATENT OFFICE

2,476,904

CARTRIDGE CASE RETRIEVER FOR FIREARMS

Claude Alfred Perry, Olton, England, assignor to
 The Birmingham Small Arms Company Limited, Small Heath, Birmingham, England, a British company

Application March 19, 1947, Serial No. 735,559
 In Great Britain May 26, 1945

Section 1, Public Law 690, August 8, 1946
 Patent expires May 26, 1965

3 Claims. (Cl. 42—35)

1

The present invention is concerned with improvements in or relating to firearms and is particularly though by no means exclusively concerned with small bore firearms of the kind used for miniature target shooting at, for example, fun-fairs.

Small bore firearms used at fun-fairs are of the blow-back kind but are initially loaded by an attendant with a plurality of cartridges and during firing spent cartridge cases are automatically ejected either from the side of the underneath portion of the firearm. In any case the cartridge cases drop at random to the ground and in the course of ejection they are liable, at least, to soil the clothing of the user or of onlookers nearby since they become fouled by reason of the explosive gases emitted upon firing. The spent cases also have some value as scrap material and it is customary to collect as many as possible for subsequent sale. As the cases are ejected at random their collection is a somewhat tedious task and usually many cases become lost, particularly if they fall on grass or sawdust.

In connection with magazine firearms, the prior art discloses that it has been proposed to provide a cartridge case retriever in the form of a bag or receptacle which is suspended by a frame removably pivoted to a fixed trigger guard, but such arrangement requires the receptacle to be detached from the firearm in order to discharge the spent cartridge cases.

It is the object of the present invention to provide an improved cartridge case retriever which constitutes an integral part of a combined trigger guard and cocking handle of the firearm, whereby the collected cases are automatically discharged upon cocking of the firearm.

In the said drawings:

Figure 1 is a sectional view of the body part of a firearm illustrative of the invention with the firing mechanism shown in uncocked position immediately after the firing of a cartridge;

Figure 2 is a view similar to Figure 1 with the firing mechanism shown in position during the action of cocking by the use of a cocking handle; and

Figure 3 is a vertical transverse section substantially on the line 3—3 in Figure 1.

The illustrative firearm is of the blow-back type and has a tubular magazine 1 in the butt end thereof from which cartridges 3 are sprung urged into the firing chamber 5. On the under portion of the body part 7 of the firearm is formed an ejection aperture 9 through which spent cartridge cases 11 are ejected. The spent cartridge

2

cases are preferably ejected by any conventional means, which forms no part of the present invention. Any convenient sear mechanism may be provided and for actuating the sear mechanism for initial cocking purposes the illustrative firearm comprises a combined C-shaped lever and trigger guard 15.

As shown in the present instance, the sear mechanism comprises a sear plate 13 pivoted at 30 to the sides of the body of the firearm and having a projection 31 thereon arranged to engage the forward peripheral edge 32 of the breech block 16 to hold the latter in retracted or cocked position, and being disengageable therefrom by a trip pawl 33 pivoted at 34 on the upper end of a trigger 35 when the latter is actuated. The breech block is pivoted on a pivot pin 17 supported in the body part 7 and is urged toward closed position by a spring 36 one end of which 15 engages a pin 37 on the breech block and the other end of which engages a pin 36^a in the body part 7. The breech block carries a firing pin 38 engageable with the rim of a cartridge in the cartridge chamber of the barrel 39 when the breech block is closed, and the breech block carries an extractor 40 which engages the rim of a cartridge case in the cartridge chamber and extracts the empty case when the breech block is retracted.

30 The cartridges 3 are fed from the magazine 1 by a feed tube 41 which is pivoted on a pivot pin 42 mounted in the sides of the body part, the feed tube riding on the arcuate periphery of the breech block so that when the latter is fully 25 retracted or cocked, the feed tube will descend and feed a cartridge to the cartridge chamber in the barrel, and when the breech block closes, the feed tube will be raised to clear the breech block.

35 The sear plate 13 is provided at its forward end with a finger 43 which rides on the arcuate periphery of the breech block, and with a shoulder 44 which is engageable by the forward end of a safety lever 45, the latter being pivoted on a pivot pin 46 mounted in the sides of the body part and provided with a spring 47 which urges its forward end toward engaging position with said shoulder. A thumb slide 48 is mounted on the top of the body part and carries a pin 49 which, while the thumb slide is in its rear position enters a recess 50 in the safety lever and thereby allows the forward end of the safety lever to engage behind the shoulder 44, and when the thumb slide is moved forwardly, the pin 49 will enter a recess 51 in the safety lever and thereby hold the latter clear of the shoulder 44.

on the sear plate. The lever 15 is pivoted on the pivot pin 17 just rearwardly of its forward end to the body part and has an upwardly extending front end portion 19 for engagement with the breech block 16 of the sear mechanism. The lever 15 extends rearwardly and at its rear end is curved upwardly and has a spring clip arrangement 21 formed thereon for co-operation with a small groove 23 in the body part to maintain the lever in normal position. Intermediate 10 its end portions the lever 15 is provided at each side thereof with upwardly extending side plates 25. The side plates merge into the opposite edges of the upwardly extending front portion 19 and are of such a height as to engage with the underside of the body part when the lever is in its normal position as aforesaid and as shown in Figure 1. Furthermore the open-ended receptacle thus formed by the plates 25 and the front portion 19 of the lever shrouds the cartridge case ejection aperture 9 so that spent cartridge cases are received therein during the use of the firearm. To prevent spent cases from falling out of the receptacle when the lever is in its normal or closed position there is provided a downwardly extending web 27 on the body part which is adapted to form the rear wall of the receptacle.

Normally in the use of a firearm of this nature the user will fire off all the cartridges therein cocking being effected automatically by explosive gases as is well understood and an indication is afforded that the magazine is empty when the trigger is actuated with no firing result. At this stage it is necessary to re-load the magazine and also manually to re-cock the firearm. In re-cocking the lever 15 will be moved downwardly and forwardly about its pivot 17 (as shown in Figure 2) thus moving the receptacle on the lever away from the web 27 and so allowing the spent cases maintained therein to drop freely away into a container or other vessel located below the firearm. In such movement of the lever its front end portion 19 will engage the breech block 16 moving the latter rearwardly to cocked position as seen in Figure 2. Thus it will be appreciated that there is provided in the illustrative firearm a means for retaining spent cartridge cases therein and a means for causing automatic discharge of the cases from the firearm during cocking thereof.

Having thus described my invention, what I

claim as new and desire to secure by Letters Patent is:

1. A firearm having in combination a body part, a breech block pivoted in the body part, a combined trigger guard and cocking handle for manually moving the breech block in cocking the firearm, the body part having an aperture formed therein through which spent cartridge cases are ejected, a receptacle formed integrally with said trigger guard and cocking handle arranged to receive and retain the spent cartridge cases when said handle is in its closed position, and to automatically discharge the cases from the firearm upon manual opening of said handle to cock the firearm.

2. A firearm having in combination a body part, a breech block pivoted in the body part, a combined trigger guard and cocking handle for manually moving the breech block in cocking the firearm, the body part having an aperture therein through which spent cartridge cases are ejected, and a receptacle formed integrally with said combined trigger guard and cocking handle for receiving and retaining the spent cartridge cases, said receptacle having an open end portion, and the firearm having a web adapted to close said end portion of the receptacle when the combined trigger guard and cocking handle is in its closed position.

3. A firearm having in combination a body part, a breech block pivoted in the body part, a combined trigger guard and cocking handle for manually moving the breech block in cocking the firearm, the body part having an aperture therein through which spent cartridge cases are ejected, and a receptacle formed integrally with said combined trigger guard and cocking handle for receiving and retaining the spent cartridge cases, said combined trigger guard and cocking handle comprising a C-shaped lever pivoted near its forward end portion and provided at its rear end with means for holding it in closed position.
